UNITED STATES PATENT OFFICE.

HENRY M. WILLIS, OF EAST WILLISTON, NEW YORK.

COVER FOR JARS, CANS, AND SIMILAR ARTICLES.

No. 824,896.

Specification of Letters Patent.

Patented July 3, 1906.

Application filed August 22, 1905. Serial No. 275,224.

To all whom it may concern:

Be it known that I, HENRY M. WILLIS, a citizen of the United States, residing in East Williston, Nassau county, and State of New York, have invented a new and useful Improvement in Covers for Jars, Cans, and Similar Articles, of which the following is a description.

This invention relates to jars, bottles, cans, &c., for holding liquids, salves, and other more or less fluid or solid substances, and particularly has reference to covers or stoppers for hermetically sealing such receptacles.

Among the objects of this invention may be noted the following: to provide a receptacle of the kind noted with a cap, cover, or stopper which will effectively prevent air reaching the contents or the latter leaking; to provide a cover for receptacles of all kinds which will completely seal the contents; to provide a cover for receptacles which cannot be jarred or shaken loose; to provide a cover for packing and storing vessels which strengthens the neck of the vessel; to provide a double cap or cover which hermetically seals the vessel to which it is applied, and to provide a cover for vessels of the kind noted having means for scraping clean the inside of the neck of the vessel as the cover is applied or set.

With these objects in view and others which will appear during the course of this description this invention consists in the parts, features, and combinations hereinafter described and claimed.

In the drawings forming part of this description, Figure 1 is a longitudinal vertical section of a jar or a receptacle having the cover of my invention applied thereto. Fig. 2 is a vertical central section of the cover removed; and Fig. 3 is a bottom plan of the cover, showing the details of the invention.

The numeral 1 denotes the body of an ordinary glass jar for holding liquids, salves, gums, &c., the neck 2 of which is provided with the usual screw-threads, as shown. This receptacle may be a can, bottle, or in any other form and of any suitable material. The cap 3 has the flange 4 threaded to correspond with the threads of the neck 2. The cap 3 has applied to it the cup-shaped device 5, the flange 6 of which depends within the neck 2, said device being secured by means of rivets 7 to said cover 3, though any other securing means may be employed within the scope of

my invention. The flanges 4 and 6 embrace the neck 2, the flange 6 closely engaging the inner surface of said neck, and between them the two flanges provide a receptacle for wax or other plastic material, such as paraffin, 8. 60 Obviously any desired quantity of the plastic material may be poured in fluid form into the flange-receptacle in order to secure the results desired, and when the cover is screwed upon the neck, as shown in Fig. 1, the latter 65 will force it into whatever space there may be between the neck and cover, thus completely sealing the receptacle. When the cover is removed and some of the contents of the receptacle extracted or poured out, more or 70 less will cling to the inside of the neck. When the cover is again applied, the flange 6 will scrape and clean said neck. This flange also strengthens the neck by bracing it on the inside and preventing a blow on the flange 4 75 from breaking or fracturing it. Moreover, the device 5 constitutes a stopper, as its flange fits snugly within the neck.

Although I have described my invention in connection with jars or other receptacles 80 provided with a neck and have specifically shown the latter feature, it is to be distinctly understood that receptacles are contemplated which are devoid of a distinctive neck and the body portion of which is provided with 85 means by which the cap, cover, or stopper may be applied thereto. In other words, my invention contemplates a receptacle of the character described and for the purposes stated with which a cap or cover of my invention may be combined and with the body portion of which about the opening the cover may coöperate.

Having thus described my invention in its details, it will be obvious that the following 95 are among its advantages: The double-flange cover affords a receptacle for the plastic material and hermetically seals the vessel; the double-flange cover braces, strengthens, and protects the neck of the vessel. By combining 100 the device 5 with the cover, a cleaner for the inside of the vessel adjacent the mouth or opening is provided, and said device constitutes a stopper which is always with the cover and is not likely, therefore, to be lost. 105

What I claim, and desire to secure by Letters Patent, is—

In combination with the neck of a vessel, a cover consisting of two cup-shaped devices one within the other, means for rigidly secur- 110

ing said devices together so that their flanges extend parallel and provide a space between the same for the reception of plastic material and the said neck, and the flange of the inner device snugly fitting the inside of said neck, so as to brace and strengthen the same and act as a cleaner therefor, substantially as described.

In testimony whereof I have hereunto signed my name in the presence of two subscribing witnesses.

HENRY M. WILLIS.
